UNITED STATES PATENT OFFICE

2,101,895

MACHINE FOR TROWELING

Harold S. Boulton, Chicago, Ill.

Application December 28, 1936, Serial No. 117,842

4 Claims. (Cl. 94—45)

My invention relates to mechanical means for troweling cementitious bodies, particularly floors, and is a modification of or variation in the construction shown in my copending application 5 Serial No. 29,901, filed July 5, 1935, Patent No. 2,065,560.

An object of my invention is to provide a troweling device in which some of the objections to the solid plate are overcome. For example, the 10 matter of suction and that of uneven wear, due to the progressively greater extent of travel of the outer portion of the disc as compared to the inner portion. By breaking up the disc into a plurality of separate plates or segments and 15 providing for reversibility of mounting, I am able to overcome the stated objections, and to provide a troweling machine that will operate through long periods without attention.

The invention will be more readily understood 20 by reference to the accompanying drawing; in which,

Fig. 1 is a side elevation showing a troweling machine constructed in accordance with my invention;

Fig. 2 is a sectional view through the center of the troweling apparatus;

Fig. 3 is a sectional view on the line 3—3 of Fig. 2; and,

Fig. 4 is a bottom plan view.

In the drawing I have illustrated a motor frame and motor 10, having a guide handle 11. To the motor driven shaft 12 is connected, by means of bolts 13 and, preferably through a resilient liner 14, a drive plate 15. Mounted beneath the drive 25 plate are a plurality of troweling plates 16, eight being shown in this instance. The edges of the plates are bevelled or turned up, as preferred, in order to offer no resistance to rotation on the relatively soft cement on which the plates will 30 operate. Leaf springs 17 are secured to the upper faces of the plates, and bolts 18, passing through suitable openings in the plate 15 and engaging the spring 17, serve as means for resilient attachment of the plates or trowels to the drive plate. 35 It will be noted that each trowel plate has two points of attachment and that the plates may be reversed; that is, turned end for end, if and when wear makes such reversal desirable. It

will be understood that the extent of travel of the outer portions of the plates will be greater than the inner portions and that there will be a tendency for proportionately greater wear on the outer portions. This may be compensated by 5 occasional end to end reversal of the plates. This is accomplished by forming the trowels symmetrical about their fastening bolts 18, thus enabling them to be reversed in position.

The number and disposition of the trowel plates 10 is a matter of selection, a larger or smaller number than those shown being possible. The form 15 of the spring connection between the trowels and the drive plate may also be changed and in other manners the construction is capable of modification within the skill of the mechanic.

I claim:

1. In a troweling machine, the combination of a horizontally rotatable carrier, a plurality of separate angularly arranged trowels mounted beneath said carrier, and a motor mounted vertically above the center of said carrier and connected to rotate the carrier and the trowels in a plane.

2. In a troweling machine, the combination of a horizontally rotatable carrier, a plurality of separate, angularly arranged trowels mounted beneath said carrier, with capacity for reversal of mounting, and a motor mounted vertically above the center of said carrier and connected to rotate 25 the carrier and trowels in a plane.

3. In a troweling machine, the combination of a rotatable carrier, a plurality of separate trowels mounted beneath said carrier, a motor superimposed on the carrier and adapted to rotate the 35 same and the trowels in a horizontal plane, and spring means interposed between the trowels and the carrier.

4. In a troweling machine, the combination of a rotatable carrier, a plurality of separate trowels mounted beneath said carrier, and symmetrically formed about their mounting attachments, thereby providing capacity for reversal of mounting, and a motor superimposed on the carrier and adapted to rotate the same and the trowels 40 in a horizontal plane.

HAROLD S. BOULTON.
